UNITED STATES PATENT OFFICE.

GEORGE HIVES DAWSON, OF BOSTON, MASSACHUSETTS, AND HURXTHAL FIELD FREASE, OF CANTON, OHIO.

TRUSSSED STRUCTURE.

Original application filed November 26, 1923, Serial No. 676,897. Divided and this application filed February 4, 1925. Serial No. 6,706.

The invention relates to trussed structures having spaced chord members and connecting web members joined together; and this application is a division of our prior application for patent for trussed structures, filed November 26, 1923, Serial No. 676,897, which has matured into Patent No. 1,526,463.

Ordinarily the chord and web members of trussed structure are separate pieces which must be made to size and assembled to form the completed structure. In the manufacture of even a simple trussed girder of substantial length, while the equivalent of a large number of chord members is attained by the use of two or more strips of the total length of the girder, yet there are still a large number of separate web members each of which must be made and punched to size and each of which must be properly assembled and fastened usually by means of rivets to the continuous equivalents of a large number of chord members. In the manufacture of such a girder the number of separate members each of which must be made to size and assembled often runs to several hundred. Due to the fact that most of these members must be fastened at each end to the co-operating members in the structure or the equivalents thereof, the number of chances for manufacturing and assembling errors, for two ended members, is double the number of members or equivalents to be assembled. Moreover in such an assembled trussed structure unequal strains and stresses are often set up in individual members due to the fact that it has been found to be a practical impossibility accurately to space and secure the fastening means which tie the truss members together at the joints.

The objects of the present invention are to economize the manufacture of trussed structures and to overcome unequal strains and stresses due to erection inaccuracies, by reducing the number of parts to be made and assembled; and these objects are attained by the use of—

Trussed elements formed from continuous strips and including spaced rows of chord members and connecting web members, there being junction angles between the chord and web members, and loops at the junction angles, and means such as lock rods fastening the loops and thereby the chord and web members to each other at the junction angles.

Moreover common transverse lock rods 55 may be used to fasten a plurality of side by side trussed elements, thereby providing lateral strength, rigidity, and stability in the trussed structural combination.

The invention is illustrated in the accompanying drawing forming part hereof, in which—

Figure 1 is an isometric view of one form of the improved trussed structural combination.

Fig. 2, is an enlarged oblique perspective view of a lock rod and a length of the improved truss structure combination having slightly different dimensions than that illustrated in Fig. 1, one pair of junction 70 angles being shown spread apart and ready for assembly by inserting the lock rod through the loops at the junction angle.

Fig. 3, an enlarged fragmentary side elevation of the improved combination at a 75 set of the joined junction angles.

While the continuous material used to form any of the various types of trussed elements embraced by the present invention may be of any desired substance; for most 80 practical purposes a continuous metallic material adapts easily to the necessary forming operations, and to assembly by the disclosed or other means.

Moreover, it is to be understood, that 85 while the material illustrated is solid, the structures of the invention may be made of perforated material, of expanded material, or of material having any other desired conformation.

Similar numerals refer to similar parts throughout the drawing.

The trussed structure 1 includes a plurality of trussed elements 2 formed from continuous strip material of any desired 95 type, but indicated in the drawing for the sake of convenience as being sheet material.

The elements 2 each include spaced chord members 3 and connecting web members 4, and there being junction angles or apexes 5 having lapped loops 6 between the chord and web members.

The trusses are fastened together by the lock and transverse reinforcing rods 7 which pass through the lapped loops as shown.

The rods 7 may, as shown, fasten and reinforce a plurality of trussed elements having apex loops to form a trussed panel

structure having strength, rigidity, and stability in all directions.

An individual-trussed element having apex loops and loop fastening or locking means 5 may be used wherever desired.

The formation and joining of the loops 6 at the junction angles are best illustrated in Figs. 2 and 3, in which a trussed element 2' is formed from a continuous strip of material of any desired type and includes spaced chord members 3' and connecting web members 4' and junction angles or apexes 5' having lapped loops 6 between the chord and web members.

15 The trussed element is fastened together by lock rods 7' which pass through the lapped loops as shown. The loops 6 are formed at the junction angles by providing longitudinal slits 8 in the continuous material at the junction angles and forming angle abutments 9 beside angle projections 10 in each junction angle, the abutments 9 in one junction angle registering with the projections 10 of its opposed angle, so that the 25 projections interfit with each other and form loops through which the lock rods may be inserted to fasten the structure together.

It is obvious that if the abutments 9 be entirely cut away, loops will be formed by 30 the interfitting projections 10 through which the lock rods may be inserted for fastening the structure, but it is preferred to retain the abutments 9 to take full advantage of all the material in the strip.

35 We claim:

1. A trussed element formed from a continuous strip and including spaced rows of chord members and connecting web mem-

bers, there being junction angles between the chord and web members, and loops at the 40 junction angles.

2. A trussed structure including a plurality of trussed elements, each element including spaced rows of chord members and connecting web members and having junction 45 angles between the chord and web members and loops at the junction angles, and common means passing through and securing the loops and the chord and web members of the elements to each other at the junction 50 angles.

3. A trussed element formed from a continuous strip and including spaced rows of chord members and connecting web members, junction angles between the chord and web members, loops at the junction angles, and means passing through and securing the loops to each other.

4. A trussed element formed from a continuous strip and including spaced rows of chord members and connecting web members, junction angles between the chord and web members, and interfitting angle projections in the junction angles.

5. A trussed element formed from a continuous strip and including spaced rows of chord members and connecting web members, junction angles between the chord and web members, and interfitting angle projections in the junction angles, and means passing 65 through and securing the angle projections to each other.

In testimony that we claim the above, we have hereunto subscribed our names.

GEORGE HIVES DAWSON.
